[57] CLAIM

The ornamental design for an ear cup, as shown and described.

DESCRIPTION

FIG. 1 is a side view of an ear cup showing my new design;
FIG. 2 is a front view thereof;
FIG. 3 is a bottom view thereof;
FIG. 4 is a top view thereof; and,
FIG. 5 is a perspective view showing two ear cups secured
to a head band; and,
FIG. 6 is a side view showing the inside of an earcup.
The strap shown in broken lines in FIG. 5 is for illustrative
purposes only and forms no part of the claimed design.
